UNITED STATES PATENT OFFICE.

AARON FREYDBERG, OF MOUNT VERNON, NEW YORK.

FABRIC BINDING STRIP.

Application filed February 12, 1923. Serial No. 618,590.

To all whom it may concern:

Be it known that I, AARON FREYDBERG, a citizen of the United States, and resident of Mount Vernon, in the county of 5 Westchester and State of New York, have invented certain new and useful Improvements in Fabric Binding Strips, of which the following is a specification.

My invention relates to fabric binding strips such as are used for making bindings and "piping" on garments, and more particularly to a bias-cut, fast-edged binding strip or roll of such binding material.

Straight-cut binding strips, that is to say, strips in which the threads of the fabric run parallel and at right angles to the longitudinal edges of the strip, are often used, and these are relatively free from a tendency to ravel at the edges; but such strips 20 are not so desirable as bias-cut strips in which the threads run diagonally in relation to the longitudinal edges because these bias strips are more readily shaped and conformed to curved portions or corners of 25 garments or other fabric structures to which the binding is applied. These bias-cut strips however ravel or split inward from the edges much more freely than the straight cut strips and for that reason have 30 to be made wider than would otherwise be necessary in order to provide wider margins of the more or less raveled edges outside the stitching, when the bindings are applied.

To obviate this difficulty my invention provides a novel fast-edged bias-cut binding strip or roll of such material, the fast-edging consisting specifically in adhesive material applied to the edges of the strip 35 and more particularly, applied to the faces of a roll formed of such a strip so that the adhesive adheres to the strip edges when the strip is run off the roll for use, and prevents raveling so that the strip may be made 40 of practically any desired width, and especially may be made as narrow as may be desired for any particular purpose, without allowance for raveling; and the firm edge 45 also permits the binding to run more freely 50 and accurately through the "binding" mechanism of sewing machines.

The method of production of the strip or strip roll takes into consideration the tendency of bias-cut strips to stretch longitudinally under moderate tension, and at 55 the same time to contract laterally. The

method of producing and fast-edging the strip or strip roll avoids or reduces such distortion of the strip.

The method, generally described, comprises cutting a wide piece of suitable strip-forming fabric diagonally to form pieces of suitable length, sewing together the selvage edges of these pieces to produce a wide strip in which the fabric threads run diagonally 60 in relation to the longitudinal edges, rolling this strip on a suitable core such as a card-board tube, severing the complete roll consisting of the fabric and the core at regular intervals to produce relatively narrow 65 individual rolls of binding strip of the proper width for the purpose in view, and applying adhesive such as a suitable glue to both faces of the individual rolls whereby all of the edges of the strip are fast- 70 edged while in roll form, this adhesive adhering to the edges of the strip when it is pulled off of the roll and preventing raveling and also tending to prevent stretching 75 and improper distortion of the strip as it is manipulated in applying it to garments and other fabrics.

The characteristics and advantages of the invention are further sufficiently explained in connection with the following detail description of the accompanying drawings which show a representative embodiment of the binding strip or roll and also illustrate one performance of the production method. After considering these exemplifications of 80 the invention persons skilled in the art will understand that many variations may be made, and I do not limit myself to details except as claimed.

Figure 1 shows a strip of full width fabric and the manner of cutting it diagonally to form individual, wide, bias-cut pieces.

Figure 2 shows the manner of connecting these pieces to form a wide strip or web and of rolling this web to produce a long 100 roll.

Figure 3 is a plan view of the long roll, illustrating the manner of cutting or severing it to produce individual binding strip rolls.

Figure 4 illustrates one manner of fast-edging the rolled strip edges.

Figure 5 is a perspective view of a completed fast-edged bias binding strip roll.

Figure 6 shows a part of the strip run off 110 of the roll ready for use.

In Figure 1, B is a roll or bolt of suitable

strip-forming fabric F. Suitable lengths of the fabric are run off of the rolls or bolts and a plurality of these pieces may be superposed; but regardless of the manner of cutting up the full-width cloth, the fabric F is cut diagonally along the lines b producing individual pieces P in which the warp and woof threads run diagonally or in bias relation to the edges b'.

10 The selvage edges a of two of these pieces P are brought together and stitched as at z, Figure 2, forming a wide strip or web W of bias-cut material which is wound upon a suitable core which is most conveniently 15 a card board tube C, forming a long roll L of bias-cut material.

This roll L is severed transversely at regular intervals as in the planes k, Figure 3, producing individual rolls R of bias binding 20 material of the desired width.

Adhesive of a suitable character such as a suitable glue is then applied to the edge faces of the rolls as sufficiently illustrated in Figure 4, producing the completed fast- 25 edged roll R, Figure 5, in which all of the cut edges of the fabric in roll form are coated with the adhesive.

Figure 6 shows a length of the binding strip S pulled off of the roll R. The edges E are coated with a sufficient quantity of the glue applied while in the roll form to cause adjacent thread ends to adhere to each other and to completely or substantially prevent raveling. The strip is really 30 in separate pieces connected by portions of the seams s which were formed when the wide bias pieces P were sewed together. These seams or connections are unobjectionable in the use of the binding. The strip 35 has all the advantages of an ordinary bias-cut strip with the added important advantage of fast-edging, which prevents raveling, and causes the strip to run more smoothly and accurately through the sewing-machine binder mechanism, and with the fur- 40 45

ther important advantage that the strip may be made originally of the exact width that is desired for use without allowance for raveled edges, thus effecting a very substantial saving in the binder material employed in 50 that a greater number of narrower rolls R may be cut from a single long roll, such as the roll L, Fig. 3, than is possible where the bias-cut binding material is not treated as herein set forth. 55

I claim:

1. As a new article of manufacture, binding material comprising a length of relatively narrow bias-cut fabric, said length consisting of a plurality of relatively narrow bias-cut pieces joined together on diagonal lines, the opposite longitudinal edges of the fabric being treated with adhesive to retard fraying tendency of the threads along such edges. 60

2. As a new article of manufacture, a roll of binding material comprising a core and a length of relatively narrow bias-cut binding fabric wound thereon, said length consisting of a plurality of relatively narrow bias-cut pieces joined together on diagonal lines, and the opposite edges of the fabric being treated with adhesive to retard the fraying tendency of the threads along such edges. 70

3. As a new article of manufacture, a roll of binding material comprising a core and a length of relatively narrow bias-cut binding fabric wound thereon, said length consisting of a plurality of relatively narrow bias-cut pieces joined together on diagonal lines, and the opposite faces of the roll being treated with adhesive to retard the fraying tendency of the threads along the longitudinal edges 80 85 of the fabric. 75

Signed at New York in the county of New York and State of New York this 5th day of February A. D. 1923.

AARON FREYDBERG.
